UNITED STATES PATENT OFFICE.

EDGAR M. BENHAM, OF NORWOOD, OHIO, ASSIGNOR TO THE MOSLER LOCK COMPANY,
OF COVINGTON, KENTUCKY, A CORPORATION OF OHIO.

TIME LOCK.

Application filed August 5, 1926. Serial No. 127,207.

This invention relates to time locks for safes, vaults, and the like, and more particularly relates to procuring protection against robbery during business hours.

5 In an application filed by me March 10, 1924, Serial No. 698,056, for time locks, I have disclosed and claimed a device associated with the ordinary time lock control for the bolt work of a safe or vault door, 10 which may be adjusted to stop the running down of the time lock at a certain stage in its normal run prior to releasing stage, so that the protected structure cannot be entered until the device has been adjusted to 15 allow the time lock to resume running and the time lock has completed the unfinished stage of its normal run. The device is adjustable from outside of the protected structure. After the protected structure has once 20 been opened, to restore the protection it has been necessary to rewind the time lock mechanism to a certain extent and to restore the interrupting device into active adjustment.

The principal object of the present invention is to improve on said protecting construction and arrangement.

More particularly, the object of this invention is to provide a device of the character described, whereby daylight protection may 30 be restored in a more simple manner, and by merely making a simple adjustment from the exterior of the structure.

A further object of my invention is to provide a protecting device of the character described, which is more durable, simpler in construction, and easier to adjust.

Other objects of this invention will be in part obvious and in part pointed out herein-after.

40 In accordance with this invention, I provide a cam, rotatable from the exterior of the structure, which, when rotated in one direction, moves the slide bar of the time lock a certain distance from releasing position, thus 45 winding up the time lock movements a certain amount. This amount is preferably about forty minutes. The locking dog is preferably spring actuated into active position with respect to the bolt work, so that, when 50 this slide bar is retracted, the dog will automatically assume position preventing the unlocking of the bolt work. When the aforementioned cam is set in operative position, it will stop and interrupt the running down 55 of the time lock mechanism, in case it shall

have been set to run for a comparatively long period of time. The structure, in such event, will remain locked indefinitely, and may not be entered until the cam has been adjusted to release the slide bar of the time lock and the 60 time elapsed for the time lock to finish the remainder of its unfinished run to releasing stage.

In order that a clearer understanding of this invention may be had, attention is hereby 65 directed to the accompanying drawings, forming a part of this application and illustrating one possible embodiment of my invention.

Referring to the drawings, Fig. 1 is an elevation of a controllable time lock mechanism embodying my invention associated with the bolt work of a protected structure, another lock being also shown associated with the bolt work; Fig. 2 is a similar view of a portion of 75 the mechanism, showing the parts in position releasing the bolt work; Fig. 3 is a sectional view of the same, and is taken on the line 3—3 of Fig. 1; and Fig. 4 is a sectional view of a detail of the construction, and is taken on 80 the line 4—4 of Fig. 1.

Similar reference characters refer to similar parts throughout the several views of the drawings.

Referring to the drawings, the time lock 85 mechanism includes one or more usual clock movements 1, each having the usual rotatable setting dials 2, pointers 3, winding stems 4, and pivoted levers 5, which are moved by the clock movements, and which, when held 90 against movement, stop the running of the clockwork. The lower end 6 of each lever 5 engages in a slot or recess 7 formed in the time lock slide bar 8. The slide bar is slidably mounted on pins 9 secured to movement 95 supporting block 9' disposed in slots 10 of the bar. At a certain stage in the running down of the time locks, the levers 5 push against the shoulders 11 of the slide bar to move it toward releasing position. This bar 100 8 has a depending lug or shoulder 12, which on such movement of the bar pushes against a pin 13 mounted on a rotatable member 14, carrying a projecting portion 15, constituting the dog for the bolt work. Member 14 is secured for rotation on the casing 16 of the mechanism by means of a screw 17. A spring 18 secured to the dog 15 and pressing against a wall of the casing constantly urges the dog 110 to move into active position and to move the

pin 13 contrary to releasing movement of the slide bar 8. Member 14 may have an extension 19 opposite the dog 15 to balance the weight of the dog and to act as a stop. When bowed, spring 18 is put under tension and pulls down on extension 19.

Slide bar 8 has another depending finger or projection 20.

A cam 21 is secured to the protected structure adjacent this finger 20 for adjustment into and out of dogging relation thereto. Preferably, this cam is secured to a sleeve 22, which is rotatable by means of a shaft 23, which engages in the sleeve, and is supplied 15 with a knob 24 disposed on the outside of the protected structure. Cam 21 is preferably provided with a small roller 25 to reduce friction between the cam and the finger 20 when the cam is rotated to move the slide bar 8 in 20 locking direction, opposing the springs of the clock movements and winding the same. Dial member has gear teeth 50 meshing with a gear 51 on the winding stem 4, and carries a pin 52 which coacts with the heel 53 of 25 lever 5, so that movement of bar 8 into locking position winds the stem 4 and sets the dial 2 to the dormant protection period, such as forty minutes.

The bolt work may assume any one of 30 various different forms. For instance, the bolt work may comprise a bar 26 slidably secured by screws 27 to the door of the structure to be protected. The bolt 28 may be carried on one end of this bar. The inner 35 end of bar 26 has a projection or end 29, which is dogged by the locking dog 15. If, in addition to the time lock, a combination or other type of lock is also desired, such lock 30 may be connected with some part of the bolt bar 26. For instance, the bolt plate 31 40 of the lock 30 may be connected to a finger 32 of the bar 26.

The operation of the protecting mechanism described above and the manner of its operation will be readily apparent. When the bolt work is released, so that the safe may be opened, the slide bar, its cam, and the locking dog are in the positions shown in Fig. 2. If it is desired to put the structure under protection during business hours, it is only necessary to turn the knob 24 sufficiently to rotate the cam 21 into the position shown in Fig. 1. This rotation of knob 24 moves the slide bar 8 a certain distance, and this movement in turn, by reason of the accompanying movement of the time lock levers 5, winds up the time lock movements a certain amount. Preferably, this operation sets the movements for a run of forty minutes or so. This movement of the slide bar 8 withdraws the projection 12 from the pin 13, whereupon the abnormally bowed spring 18 causes the locking dog to rotate into active position, dogging the bolt work.

Now, in the course of the business day, no

person may enter the protected structure until he has adjusted the knob 24 to withdraw the cam 21 from the finger 20 of the slide bar 8, and then has waited the required forty minutes, or so, which must be consumed before the time lock movements have moved the slide bar 8 into releasing position. With such protection, it is believed that the structure is safe against daylight burglars, since it is not believed that burglars would care 70 to wait the required length of time before entrance may be had to the protected structure after making releasing adjustment of the knob 24.

With a device of the character described, 80 there is no interference with the setting of the time lock movements for longer periods of time. This longer adjustment may be accomplished in the usual way by means of the customary key applied to the winding posts 85 4. However, if the cam 21 has been adjusted into active position, the running down of the time locks will be interrupted and stopped at the comparatively short interval before releasing stage. Thus, the protected 90 structure will remain locked indefinitely and until the cam 21 is adjusted out of active position and the time locks have run through the final stage. If such interruption is not desired, it is merely necessary to adjust the cam 21 out of active position before the slide bar has engaged the same.

From the above, it will be apparent that the above construction and arrangement guards a protected structure securely against 100 daylight robbery, and after an opening of the structure, permits the restoration of this protection in a very simple and easy manner, which does not require the application of the winding key to the time lock movements.

As many changes could be made in the above construction and as many apparently widely different embodiments of this invention could be made without departing from the scope thereof, it is intended that all matter 110 contained in the above description or shown in the accompanying drawings shall be interpreted as illustrative and not in a limiting sense.

What I claim is:—

1. The combination with a structure to be protected, of a locking dog, time lock mechanism including clockwork, a slide bar dominating movement of the locking dog, means connecting the time lock mechanism and slide bar whereby the running down of the clockwork moves the slide bar in one direction to release the locking dog and whereby movement of the slide bar in the reverse direction winds up the clockwork, and means operable 120 from the exterior of the structure to move said slide bar in the direction resulting in the winding up of the clockwork.

2. The combination with a structure to be protected, of a locking dog, time lock mech- 130

- anism including clockwork, a slide bar dominating movement of the locking dog, means connecting the time lock mechanism and slide bar whereby the running down of the clock- 25
5 work moves the slide bar in one direction to release the locking dog and whereby movement of the slide bar in the reverse direction winds up the clockwork, and means operable from the exterior of the structure to move 10
10 said slide bar in the direction resulting in the winding up of the clockwork, said means last mentioned constituting a device for preventing movement of the slide bar by said clock- work. 15
15 3. The combination with a structure to be protected, of time lock mechanism including clockwork, a slide bar, means connecting the time lock mechanism and slide bar whereby the running down of the clockwork moves 20
20 the slide bar in one direction and whereby movement of the slide bar in the reverse direction winds up the clockwork, means operable from the exterior of the structure to move said slide bar in the direction resulting in
- the winding up of the clockwork, a locking 25
dog, means whereby movement of said slide bar by the clockwork moves said dog out of active position, and means whereby the locking dog is moved into active position when the slide bar is moved in the opposite direction. 30
4. The combination with the slide bar of a time lock mechanism, of a cam coacting with said slide bar, said cam being rotatable to retract said slide bar and to assume position preventing forward movement of the slide 35
bar, and adjustable into position permitting forward movement of the slide bar, a locking dog, a spring urging said dog into active position, and a connection between the slide bar and the locking dog whereby movement 40
of the slide bar in releasing direction moves the dog out of active position, said spring moving the dog into active position when the slide bar is retracted. 45

This specification signed this 23d day of July, 1926.

EDGAR M. BENHAM.
